UNITED STATES PATENT OFFICE.

JAMES A. GUEST, OF BURLINGTON, IOWA.

DESK.

SPECIFICATION forming part of Letters Patent No. 270,895, dated January 23, 1883.

Application filed March 2, 1882. (No model.)

To all whom it may concern:

Be it known that I, JAMES A. GUEST, a native-born citizen of the United States, residing at Burlington, in the county of Des Moines and State of Iowa, have invented certain new and useful Improvements in Desks; and I do hereby declare the following to be a full, clear, and exact description of the invention, such as will enable others skilled in the art to which it appertains to make and use the same.

This invention relates to desks; and it consists in constructions and combinations of parts hereinafter described and set forth in the claims hereto annexed.

15 In the accompanying drawings, which illustrate my invention and form a part of this specification, Figure 1 is a front elevation. Fig. 2 is a side elevation, partly in section, in the line *xx* in Fig. 1. Figs. 3, 4, 5, and 6 are detail elevations and sections, hereinafter referred to. Fig. 7 is a horizontal section on line *zz* of Fig. 8. Fig. 8 is an elevation of the desks, showing the cases in position for passing over the polygonal wheels.

25 Referring to the drawings by letters, the same letter indicating the same part in the different figures, letter A represents a desk, which may be constructed as shown or in any desired manner. As shown it is provided with 30 surfaces *a*, on which writing or other work may be performed, and with central higher parts, *a'*, which contain receptacles for books, papers, or other articles.

From and between the parts *a a* a frame, B, 35 projects upwardly, for purposes hereinafter described. The frame B is stayed by transverse bars *b*. As shown, the parts *a* extend outward in front and rear of the frame B, as shown at Fig. 2, to form what may be termed a "double desk," each one of which has two surfaces, *a*, as shown in elevation at Fig. 1.

40 C is a shaft extending outward at both ends through the sides of the desk and provided at each outer end with a pulley, *c*. On each 45 side of the desk, and convenient to a person sitting at either side, *a*, in front or in rear of the frame B, is a hand-wheel, C', one of which is geared by a belt, *c'*, with the pulley on one end of the shaft C and the other with the pulley on its other end.

45 D D are chain-wheels fixed on the shaft C, and may be either sprocket-wheels or poly-

gonal wheels; but I prefer polygonal wheels of the class shown in the drawings.

E E are chain-wheels journaled at the upper end of the frame B, each on a short shaft, *e*, which projects inwardly from its adjacent side of the case B in such manner as to leave the space free between said wheels. The wheels E E may be journaled on or secured to the same shaft; but I prefer to journal them on separate shafts, so as to permit of the use of larger cases passing and swinging over between them, as hereinafter described. Endless chain-belts F F pass over the upper and lower 55 chain-wheels, as shown.

G are cases hinged or journaled to the chain-belts F F in such manner as to always retain the same side uppermost as they are carried around by the movement of the belts when 60 the chain-wheels D are rotated. In the drawings two methods of hinging the cases G to the chain-belts are shown, the one which I prefer being more plainly shown at Figs. 4 and 6 and the other, shown at Fig. 5, being a modification thereof.

65 H is a rod extending across the top or near the top of case G, and loosely through a bracket, *g*, at each side of said case. The projecting ends of the rod H are inserted respectively in holes in the adjacent chain-belts F loosely, so that they may permit rotation of the rod therein. The rods H are held in place by spring-catches *h*, which are seated in recesses *h'* in said rods, and engage with notches 70 *f* in the chain-belt, as shown at Fig. 4. By pressing down the spring-catch *h* the rod H may be withdrawn to remove its connected case G, or for any other purpose.

75 At Fig. 5 brackets I are shown attached 90 one to each side of a case, G, at or near the upper side of said case, with ends *i*, which are rounded and adapted to journal in the chain-belts, same as the rod H.

80 The cases G may contain drawers in various 95 numbers, as shown at Figs. 1 and 5, or they may have hinged sides, as shown at Figs. 1, 3, and 6, or they may be constructed in any manner desired, and be adapted to contain any desired articles, and may be furnished 100 with doors, drawers, or other devices on one side only, or on both sides, for use by persons on either the front or rear side of the desk.

J is a catch held by a spring in its normal

position, in contact with a toothed wheel, *j*, on the shaft *C*.

K is a foot-treadle, connected by a cord or rod, *k*, with the spring-catch *J*.

5 *L* are bars, against which the cases *G* rest, to prevent them swinging inward when drawers are thrust into them, and at such other times as required.

The cases *G* may be supplied with books, 10 papers, or any articles or things desired for by the person or persons using the desk, and the frame *B* may be made of such height as to contain as many cases *G* as will be required.

To bring either case *G* to within easy reach 15 of the persons at the desk the catch *J* may be released from the wheel *j* by pressing with the foot on the treadle *K*, and then by means of either hand-wheel *C'* the shaft may be rotated in either direction to drive the chain-belts, so 20 as to bring the desired case or cases *G* into convenient positions for access thereto, when the foot-treadle may be released to allow the spring-catch to operate and hold the cases as desired. The cases *G* being suspended at 25 points above their respective centers of gravity, will retain the same upright positions in every part of their paths as they are carried by the chain-belts over the upper chain-wheels and below the lower ones, as plainly shown at

30 Fig. 2.

Having thus described my invention, what I claim as new, and desire to secure by Letters Patent, is—

1. In a double desk having an upright frame, the endless chain-belts *F*, passing over polygonal wheels *D*, and provided with gravitating cases *G*, and adapted to carry said cases into convenient position for access thereto on either side of the desk, in combination with operating mechanism, consisting of shaft *C*, pulley *c*, 40 hand-wheel *C'*, and belt *c'*, all substantially as set forth.

2. In a double desk having an upright frame, the endless chain-belts *F*, passing over polygonal wheels *D*, and provided with gravitating cases *G*, and adapted to carry said cases into convenient position for access thereto on either side of the desk, in combination with operating mechanism, consisting of shaft *C*, pulley *c*, hand-wheel *C'*, and belt *c'*, 45 and a spring-catch, *J*, all substantially as set forth.

3. The desk herein described, consisting of case *A*, having double working-surfaces *a* *a'*, the raised part *a'*, and upright frame *B*, in which is arranged an elevator with gravitating cases *G*, having suitable brackets for pivoting them to the elevator-chain, and operated by mechanism as herein described, with the spring-catch *J* and foot-treadle *K*, all arranged substantially as and for the purpose specified. 55

In testimony whereof I affix my signature in presence of two witnesses.

JAMES A. GUEST.
